UNITED STATES PATENT OFFICE.

EDWARD J. TOMLINSON, OF NEWARK, NEW JERSEY. ASSIGNOR TO SPLITDORF ELECTRICAL COMPANY, OF NEWARK, NEW JERSEY.

PHONOGRAPH-STOP.

1,399,327.

Specification of Letters Patent.

Patented Dec. 6, 1921.

Application filed October 27, 1919. Serial No. 333,800.

To all whom it may concern:

Be it known that I, EDWARD J. TOMLINSON, a citizen of the United States, residing at Newark, in the county of Essex, State of New Jersey, have invented certain new and useful Improvements in a Phonograph-Stop, of which the following is a description, reference being had to the accompanying drawing and to the figures of reference marked 10 thereon.

This invention relates to a stop for phonographs and as illustrated is particularly adapted for use in connection with an electrically operated one.

15 It is the principal object of my invention to provide an automatic stop for a phonograph so that after the sound record has been played the stopping mechanism will be automatically brought into play thereby 20 preventing the motor from driving the record and injuring both it and the needle.

As illustrated in the drawings, my automatic stop is particularly adapted for use in connection with the type of motor shown 25 in my application, Serial No. 308,840, filed July 5, 1919, although it will be understood that it may be applied to other types of motors.

In the drawings, Figure 1 illustrates the 30 end of a tone arm carrying the reproducer and one form of stopping mechanism.

Fig. 2 is an end view of Fig. 1.

Fig. 3 is a diagrammatic view of the electrical circuit showing the application to an 35 electrically operated motor.

Fig. 4 is a side view of the tone arm showing another form of stop.

Fig. 5 is a bottom view of Fig. 4.

Fig. 6 is a view similar to Fig. 4 but with 40 the stopping mechanism in another position of operation.

Fig. 7 shows a detail of part of the stopping mechanism.

Referring now to the details, wherein like 45 numbers refer to corresponding parts in the various views, 1 illustrates a tone arm to which reproducer 2 is attached. The reproducer carries the usual playing needle 3 which is shown in Fig. 1 in contact with the 50 sound record body 4. Attached to the tone arm 1 by a stud 5 is a light flexible member 6, the member 6 being pivoted on the stud 5. The end of the flexible member carries a second needle 7. The needle 7 may be carried at the end of member 6 in any suitable

manner so that if necessary it may be removed for renewal, although the pressure of needle 7 on the sound record body 4 is extremely light for a purpose hereinafter referred to.

60 The end of the member 6 is preferably covered with a layer of tape 8 so as to deaden any vibration that may be picked up by the needle 7 and transmitted to the tone arm through the mounting stud 5. The needle 7 is held in a displaced position with reference to needle 3 as shown in Fig. 2, by means of a spring 9, the tension of which is adjusted by screw 10.

65 As shown diagrammatically in Fig. 3, 11 70 illustrates the motor or motor winding which operates the phonograph, 12 being a circuit breaker and 13 a governor, both used for actuating and controlling the motor 11 at the proper time, all as set forth in my application above referred to. 14 illustrates 75 an electromagnet which controls the starting and stopping switch of the motor 11. The switch 15 is illustrated in circuit with the electromagnet 14. A stop 16 is carried by 80 the tone arm 1 but insulated therefrom and extending from the stop 16 is a conductor 17 extending to the electromagnet 14. The end of the arm 6 is bent so as to have an end 18 adapted to engage the stop 16 and when 85 such engagement is made it will be seen that a circuit is closed from the source of current B through the stopping electromagnet 14, stop 16 and member 6.

90 In operation, when the playing needle 3 is placed in position on the sound record body and the phonograph started, the needle 7 will trail along behind the playing needle 3, as shown in Fig. 2, but with very light pressure on the record so as not to injure it in any manner. In the construction 95 of sound records, several grooves are left blank on the record disk and the playing needle 3 when it reaches the end of these blank grooves can carry the tone arm no 100 farther inward toward the center of the sound record body but the needle 7 being free to move about the pivot stud 5 will swing on the pivot until the end 18 comes in contact with stop 16 thereby closing the 105 electrical circuit through the stopping magnet 14 which will operate and release the switch controlling the starting and stopping of the phonograph motor.

110 In order to overcome any objection to a

second needle such as 7 running over the record, I have provided an arrangement such as shown in Figs. 4 to 7 inclusive, wherein the needle 7 is held out of engagement with the sound record body until after the record has been played. This is brought about by means of a bracket 19 carried on part of the phonograph independent from the tone arm and which bracket has an arm 20 with upturned edges 21. The end 18 of light member 6 is adapted to be normally held underneath the arm 20, as shown in Fig. 4, thereby holding the member 6 so that the needle 7 is kept out of engagement with the sound record body 4, but as soon as the tone arm 1 has moved to a predetermined position the end 18 of the member 6 will pass from under the arm 20, as shown in Fig. 5, and the needle 7 will be carried onto the sound record body 4 by means of a spring 22. This particular movement of the arm 6 is brought about just before the needle 3 reaches the end of the dead grooves in the sound record body. The needle 7 when it is dropped onto the record is in a displaced position, shown in Fig. 5, and as heretofore described with reference to Figs. 1 and 2. It will then be moved about its pivotal mounting 23 against the tension of spring 24 that normally holds it in its displaced position. The pivotal stud 23 is held to the tone arm by a bracket 25 in any suitable manner, such as by screws 26. Continued rotation of the sound record body will carry the member 6 to the dotted position 27, whereby the end 18 of the member 6 will engage the stop 16 with the results heretofore explained.

It will be understood that various changes may be made in the details relating to my invention without departing from the spirit of the same and the scope of the appended claims.

Having thus described my invention, what I claim is:—

1. In a phonograph, the combination of a sound record body, motor means for driving said sound record body, a tone arm carrying a reproducer having a playing needle, means for stopping said motor means and a second needle carried by the tone arm for actuating the stopping means, but normally out of engagement with the sound record body, means for dropping the second mentioned needle onto the sound record body after the playing needle has finished playing the record, said sound record body acting to move the second needle, after it has been dropped into engagement therewith, to a position for bringing said stopping means into operation.

2. In a phonograph, the combination of a sound record body, motor means for driving

said sound record body, a tone arm carrying a reproducer having a playing needle, means for stopping said motor means and a second needle for actuating the stopping means pivotally mounted on the tone arm, means for holding said second needle out of engagement with the sound record body until after the record has been played by the first needle and then releasing it, means for moving the second needle onto the sound record body after it has been released, said sound record body acting to rotate the second needle to a position where it actuates the stopping means as described.

3. In a phonograph, the combination of a sound record body, motor means for driving said sound record body, a tone arm carrying a reproducer having a playing needle, means for stopping said motor means and a second needle normally out of engagement with the sound record body for actuating the stopping means but pivotally mounted on the tone arm for movement in two directions, means independent of the tone arm for holding said second needle from movement toward the sound record until after the record has been played and then releasing it, means carried on the tone arm for moving the second needle about its pivot onto the sound record body after it has been released by said holding means, said sound record body acting on the second needle to move it in another direction about its pivot whereby it brings said stopping means into operation.

4. In a phonograph, the combination of a sound record body, motor means for driving said sound record body, a tone arm carrying a reproducer having a playing needle, means for stopping said motor means and a second needle carried by the tone arm but operated by the sound record body for bringing said stopping means into operation, and means associated with the second needle to deaden sound vibrations transmitted thereto by the sound record body.

5. In a phonograph, the combination of a sound record body, motor means for driving said sound record body, a tone arm carrying a reproducer having a playing needle, means for stopping said motor means, a second needle operated by the sound record body for bringing said stopping means into operation, a resilient connection between said second needle and the tone arm and a sound deadening material wrapped around the resilient portion to deaden sound vibrations transmitted to the second needle by the sound record body.

In testimony whereof, I affix my signature.

EDWARD J. TOMLINSON.
